PROMPTING DEVICE FOR CAMERA MOUNTING

Joseph Barrera, 425 Neptune Blvd., Long Beach, N.Y.

Filed Aug. 12, 1958, Ser. No. 52,171

Term of patent 14 years

(Cl. D61—1)

FIG. 1

FIG. 3

FIG. 2

Fig. 1 is a front elevation view of a prompting device for camera mounting, showing my new design;

Fig. 2 is a side perspective view, the opposite side being similar in appearance but differing as to the offset of the hood relative to the base, as will be understood from a comparison of the right side of Fig. 1 with respect to the left side thereof and the left side of Fig. 3 with respect to the right side thereof; and

Fig. 3 is a rear elevational view thereof.

The dominant features of my new design are shown in solid lines in the drawing.

The broken line showing of a changeable script and legible matter thereon is for illustrative purposes only.

I claim:

The ornamental design for a prompting device for camera mounting, as shown and described.
